RING TRAVELER COMPANY, OF PROVIDENCE, RHODE ISLAND, A CORPORATION
OF RHODE ISLAND.

RING-TRAVELER.

1,121,378.

Specification of Letters Patent. Patented Dec. 15, 1914.

Application filed June 29, 1914. Serial No. 847,872.

To all whom it may concern:

Be it known that I, WILGER T. LANCASTER, a citizen of the United States of America, and a resident of Ashton, in the State of 5 Rhode Island, have invented a new and useful Improvement in Ring-Travelers. of which the following is a specification.

This invention relates to travelers for ring spinning; and it consists in a "bevel-top" ring traveler of improved construction, and in the combination of the same with a horizontally flanged ring as herein-after particularly described and claimed.

In common with numerous previous "im- 15 provements", the bevel-top traveler of the present invention is an improvement on the ordinary C-shaped traveler, the patents for which have expired; and said bevel-top traveler is therefore shown in contrast to 20 said C-shaped traveler in the drawings hereinafter referred to.

The leading objects of this invention are: to reduce the length of the material in the traveler, so as to add the weight of the 25 length saved in greater thickness of metal for longer wear; to render the improved traveler better balanced from the contact or bearing at its inner horn, where centrifugal force throws it against the inner flange 30 of the ring; to adapt the improved traveler to wear flatter or more evenly at this point of primary ring contact or bearing; and to adapt the improved traveler to be kept in a horizontal or balanced position with a 35 lighter strain upon the thread than has heretofore been practicable.

Other objects will be set forth in the general description, which follows.

A sheet of drawings accompanies this 40 specification as part thereof.

Figures 1 and 2 are conventional elevations partly in section showing an improved bevel-top traveler in contrast with a C-shaped traveler at the beginning and end of 45 a ring spinning operation, respectively; Fig. 3 represents a magnified section through an I-shaped ring, showing the said improved traveler on a larger scale.

Like reference characters refer to like 50 parts in all the figures.

The horizontally flanged ring represented at α is of an ordinary I section. See Fig. 3. The bevel-top traveler b combined therewith is of improved construction. An ordinary C-shaped traveler is represented by

way of contrast at c . An ordinary bobbin is represented at d ; the thread eye at e , and one and the same thread running from the thread eye e through the traveler b or c to the bobbin d , is represented at f .

The improved bevel-top traveler b , as compared with the C-shaped traveler c , obviously requires a considerably reduced length of the ordinary metal from which its blank is cut; and can consequently be made 60 of a given weight from thicker material, so as to wear longer. The same is true to a greater or less extent of the improved traveler as compared with travelers of other known forms. In so reducing the 65 length of the metal, the improved traveler is given the "bevel-top" shape represented in the several figures. In Fig. 3 its inner and outer contact horns are represented at 1 and 2, respectively; its bevel top at 70 3, and its outwardly rounded side or end portions connecting said bevel top with said horns 1 and 2 respectively, are represented at 4 and 5. The horns 1 and 2 are in line with each other and normally horizontal. 75 The inner horn 1 adjoins the larger and heavier rounded portion 4. The outer horn 2 is about one-third longer than the inner horn, but the outer side of the traveler including the smaller curved portion 5 is 80 lighter than the inner side, being reduced in weight about one-third as compared with said inner side. One effect of so reducing the outer side of the improved traveler b 85 between its outer horn 2 and its bevel top 3 is to adapt the improved traveler to find and maintain an effective balancing position 90 without any contact of the outer horn 2 with the ring. Previous travelers as represented at c drop down more or less at the outer 95 side, and occasionally the outer horn comes in contact with the outer side of the ring α , and sometimes rubs so hard under centrifugal force as to cut into the side of the ring or to draw the temper of the traveler.

The improved bevel-top traveler b is designed and adapted to run in the balanced position in which it is shown in the accompanying drawings, whether the bobbin be empty as in Fig. 1 or full as in Fig. 2, and whether the ring be in its uppermost position, as shown at the top in each of these figures, or in its lowermost position, represented at the bottom in Figs. 1 and 2. In said balanced position, the horns 1 and 2 of 100 105 110

the bevel-top traveler *b* are horizontal as aforesaid, and a flatter or more even wear on the upper surface of the inner horn 1 where it contacts with the inner flange 1' of 5 the ring *a* is thus insured; the pull of the thread *f* keeping the entire length of said inner horn 1 in contact with said ring flange 1'. All the rest of the improved traveler, in its said balanced position, is free from 10 contact with the ring, and the revolving traveler is thus adapted to run lighter and smoother, as well as with a flatter and consequently a longer wear, as compared with said previous forms represented at *e*. Owing 15 to said saving in wear, a given weight of the improved bevel-top traveler will last 100% longer as compared with said old forms; and running lighter, weight for weight, makes it possible to run travelers 20 three or four numbers heavier than is possible with other forms for a given size of thread; a relatively light strain on the thread sufficing to control a given weight of traveler. Insuring a flat wear on the inner 25 horn 1 of the improved traveler *b* is also advantageous in view of the fact that the uneven wear of the inner horn due to the tilting over of old forms of traveler at the outer side of the ring *a*, as represented at *c*, ex- 30 tends into the bend between the inner horn and the inner side of the traveler, where strength is most essential; and sometimes to those portions of the inner side of the traveler which contact with the thread, caus- 35 ing them to cut the thread.

The extremity of the elongated outer horn 2 contacting with the outer side of the ring *a* prevents the reduced side or end 5 of the improved traveler *b* from coming in contact 40 with the outer flange 2' of the ring at the instant when the spinning machine is being stopped or started and the traveler is pulled inward by the thread. At all other times the revolving traveler is thrown outward by 45 centrifugal force. When so pulled inward,

at the instant of stopping or starting, the reduced traveler would bind by contact with said outer flange 2', but for the endwise contact of said elongated outer horn 2.

Having thus described said improvement, 50 I claim as my invention, and desire to patent under this specification.

1. An improved ring traveler having an inner horn adapted to form its primary ring contact, an outer horn of greater length, 55 a bevel top, an outwardly curved portion connecting said inner horn with said bevel top and adapted to contact with the thread, and an outwardly curved portion connecting said outer horn with said bevel top and 60 reduced relatively to the curved portion first named:

2. In combination with a horizontally flanged ring, a normally balanced bevel-top ring traveler having an inner wear-deter- 65 mining horn adapted to contact flatwise with the inner flange of the ring, and an outer horn of greater length adapted to contact endwise with the ring when the traveler is not balanced by centrifugal force. 70

3. In combination with a ring of I-section, a bevel-top ring traveler, normally balanced by centrifugal force and the pull of the thread, said traveler having an inner wear- 75 determining horn adapted to contact flat- wise with the inner flange of the ring, an outer horn of greater length adapted to contact endwise with the ring when the traveler is starting or stopping, an outwardly curved portion connecting said inner horn with 80 said bevel top and adapted to contact with the thread, and an outwardly curved reduced portion connecting said outer horn with said bevel top, substantially as hereinbefore specified. 85
